United States Patent

Des. 235,654
Patented July 1, 1975

235,654

DISPLAY TERMINAL

David K. Crabbe, Auburn, Leonard F. Halio, Stow, and
John W. Carroll, Pepperell, Mass., assignors to Digital
Equipment Corporation, Maynard, Mass.

Filed Sept. 26, 1973, Ser. No. 401,924

Term of patent 14 years

Int. Cl. D14—02

U.S. Cl. D26—5 C

FIG. 1

FIG. 2

FIG. 3

FIG. 1 is a perspective view of a display terminal embodying our new design;

FIG. 2 is a view from the front thereof;

FIG. 3 is a view from the left side thereof, the view from the right side being substantially identical thereto. The rear of the display terminal is unornamented.

We claim:

The ornamental design for a display terminal, substantially as shown and described.
